GEORGE DUTTON, OF UNO, MANITOBA, CANADA.

OIL CAN.

1,412,173.

Specification of Letters Patent. Patented Apr. 11, 1922.

Application filed October 7, 1919. Serial No. 328,992.

To all whom it may concern:

Be it known that I, GEORGE DUTTON, of the village of Uno, in the Province of Manitoba, Canada, have invented new and useful Improvements in Oil Cans, of which the following is the specification.

The invention relates to improvements in oil cans and particularly to a forced feed can, and the principal object of the invention is to provide a simply constructed, inexpensive and durable can which can be easily and quickly filled by the manipulation of a plunger, and from which the oil can be positively expelled by operating the plunger.

With the above object in view the invention consists essentially in the arrangement and construction of parts hereinafter more particularly described, and later pointed out in the appended claims, reference being had to the accompanying drawing in which:

Fig. 1 is a side view of the oil can.

Fig. 2 is a vertical sectional view centrally through the can.

Fig. 3 is an enlarged detailed sectional view through the front end of the can.

In the drawing like characters of reference indicate corresponding parts in the several figures.

1 is the body of the can which is cylindrical and has the lower end cut away at an angle and closed by a base piece 2, the arrangement being such that when the can is resting on the base the body thereof sits at an angle of approximately 45 degrees to the horizontal.

The front end of the can is shaped to present a bulging nose 3 and immediately above this nose I locate the outlet spout 4 which extends upwardly and terminates in a contracted discharge end 5, which curves forwardly and is located above the level of the rear part of the can body. By this arrangement it will be apparent that the oil will not overflow from the spout should the can body be filled full.

In the nose I solder a filling pipe 6 which is provided with a shoulder 7, and receives a removable screw cap 8 which is actually screwed against the washer 9 seating on the shoulder. The upper end of the can body is closed by a top or cap piece 10 which is provided with air outlet openings 11.

12 is a cup washer preferably made from leather, which washer is permanently

riveted to a metallic disc 13, the disc and washer actually forming a plunger slidably mounted within the cylinder.

14 is a plunger rod having the inner end bent at right angles to the body and soldered centrally to the disc and the outer end extending slidably through the cap 11 and fitted with a finger piece 15.

16 is a handle suitably fastened to the rear side of the cylinder.

When this can is to be used the screw cap 8 is removed and the plunger is drawn out of the cylinder by pulling on the plunger rod. This effects the drawing in of the oil and the filling of the can. Afterwards the screw cap is replaced and the can is ready for use, the operator pushing in on the finger piece each time he desires to expel oil through the spout.

The openings 11 allow of the escape of air from the upper end of the cylinder.

What I claim as my invention is:

1. In an oil can an inclined can body provided with a closed top and bottom, a spout leading from the upper side of the can and adjacent to the bottom, a plunger operatively mounted within the can body in sliding engagement therewith, a plunger rod extending from the plunger and a filling opening located at the base of the spout.

2. In an oil can, a cylindrical can body having the upper end closed and the lower end cut at an angle and closed by a base piece, an upwardly extending spout communicating with the top side of the cylinder in a location adjacent the base, a filling plug located at the front end of the cylinder directly beneath the spout, a plunger slidably mounted within the cylinder in sliding engagement therewith, a plunger rod extending from the plunger out the upper end of the cylinder, and a handle for the can.

3. In an oil can, a can body in the form of a frustum of a cylinder having closed ends and with the inclined end forming the base of the can, a spout communicating with the top side of the cylinder in a location adjacent to the base, a removable filling cap located directly beneath the spout, a plunger operatively mounted within the cylinder in sliding engagement therewith, a plunger rod extending from the plunger and out the top of the cylinder and a handle located on the side of the cylinder remote from the spout.

4. An oil can comprising a horizontal lower end wall forming a supporting base, an inclined cylindrical body rising from said base and closed at its upper end, an integral spout extending outwardly from the upper side of the body adjacent the lower end thereof, a filling pipe extended through the lower end of said body below said spout and equipped with a cap closing the outer end thereof, and a plunger having a close sliding fit in said body above the spout and

operable to fill the can through the filling pipe or to dispose the contents of the can through the spout.

Signed at Minniota, this 13th day of 15 August 1919.

GEORGE DUTTON.
